US0D1081478S

(12) **United States Design Patent** (10) **Patent No.:** **US D1,081,478 S**
(45) **Date of Patent:** **** Jul. 1, 2025**

(54) **MOTORCYCLE SIDE SPOILER**

(71) Applicant: **KTM AG**, Mattighofen (AT)

(72) Inventors: **Marco Hubmann**, Judenburg (AT);
Stefan Krenn, Judenburg (AT)

(73) Assignee: **KTM AG**, Mattighofen (AT)

(**) Term: **15 Years**

(21) Appl. No.: **29/935,573**

(22) Filed: **Apr. 2, 2024**

(30) **Foreign Application Priority Data**

Jan. 2, 2024 (DE) 20 2024 100 002.1

(51) **LOC (15) Cl.** **12-11**

(52) **U.S. Cl.**

USPC **D12/114**; D12/126

(58) **Field of Classification Search**

USPC D12/114, 117, 110, 126, 181, 186

CPC B62K 11/00; B62K 11/02; B62K 11/04;

B62J 17/00

See application file for complete search history.
